CLAIM

The ornamental design for a pet food container as shown.

DESCRIPTION

FIG. 1 is a front, right, and top perspective view of a pet food container, showing my new design;

FIG. 2 is a rear, left, and bottom elevation view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled area labeled "9" in FIG. 1;

FIG. 10 is an enlarged view of an encircled area labeled "10" in FIG. 1; and,

FIG. 11 is an enlarged view of an encircled area labeled "11" in FIG. 2.

The evenly-dashed broken lines depict portions of the pet food container that form no part of the claimed design. The dot-dash broken lines shown in FIGS. 1, 2, 9, 10, and 11 framing portions of the pet food container for enlargements purposes form no part of the claimed design.

1 Claim, 11 Drawing Sheets
